UNITED STATES PATENT OFFICE.

JOSEPH RETALLACK, OF CENTRAL CITY, ASSIGNOR OF TWO-THIRDS TO
OLIVER S. UNDERHILL, OF SOUTH PUEBLO, COLORADO.

COMBINED MINER'S CANDLE-HOLDER AND FUSE-CUTTER.

SPECIFICATION forming part of Letters Patent No. 267,110, dated November 7, 1882.

Application filed October 6, 1881. (No model.)

To all whom it may concern:

Be it known that I, JOSEPH RETALLACK, of Central City, in the county of Gilpin and State of Colorado, have invented a new and Improved Combined Miner's Candle-Holder and Fuse-Cutter, of which the following is a specification.

The object of my invention is to provide a new and improved folding combined candle-holder and scissors or shears for cutting a fuse.

The invention consists of a U-shaped spring-frame, to one shank of which a spring-ring is attached for holding and receiving a candle, which ring is provided with a lug or finger for opening it to admit the candle. Two sharp-edged blades are pivoted between the ends of the U-shaped frame, and form scissors or cutters for cutting a fuse and for fastening a cap on a fuse.

Reference is to be had to the accompanying drawings, forming part of this specification, in which similar letters of reference indicate corresponding parts in all the figures.

Figure 1 is a perspective view of my improved candle-holder, showing the blades partly opened. Fig. 2 is a plan view of the same, showing the blades closed.

One end of a circularly-bent metal strip, A, the ends of which are not united, and which forms a spring-ring, B, is riveted or otherwise attached to the end of a shank of a U-shaped spring-frame, C, the ends of the shanks of which are brought together. The spring-ring B is provided with an elongation or finger, D, on the side 35 toward the frame C, and by pressing this finger toward the frame C the ring B can be opened to admit the candle, which is held in this ring by the spring-power of the same. Two sharp-edged blades, E and F, are pivoted between the ends of the shanks of the spring-frame C, and the frame and the eyes of these blades are provided with locking notches and recesses arranged a quarter of a circle from each other, as shown at G, so that the blades will be held 40 in various positions. The blade E is straight.

and has a sharp point, and the end of the blade F is also pointed, but is bent to form a hook, H. The cutting-edges of these blades are provided with a series of notches, J, in which the cutting-edges are very sharp, and with flat recesses J' J', in which the cutting-edges need not be sharp. The blades E and F must be of such length that when folded they can be easily contained within the spring-frame C, which serves as a handle for the candle-holder. If a fuse is to be cut, the blades E and F are separated, as shown in Fig. 1, and the fuse is placed in the notch J and the other blade is closed down, whereby the fuse will be cut. If a cap is to be attached to a fuse, the end of the fuse 50 is placed into the cap and the cap placed in one of the recesses J, upon which the other blade is closed down for the purpose of pressing part of the sides of the cap into the fuse for holding the fuse in the cap. The hook H 55 serves to suspend the candle-holder from a projection, shelf, or bracket, and the blade E can be driven into a crevice of the rocks, or into a beam, whereby the candle-holder can be fastened in any desired position. The apparatus can be folded to occupy little space.

Any suitable kind of cutting device can be combined with the candle-holding socket; but I prefer to use the two pivoted blades E F and a spring-frame for holding them.

Having fully described my invention, what I claim as new, and desire to secure by Letters Patent, is—

The combination, with the U-shaped spring-handle C, of the candle-holder B and the cutter-blades E and F, pivoted between the free ends of the handle, said cutter-blades being provided with notches J and J' and adapted to be folded within the handle, substantially as set forth.

JOSEPH RETALLACK.
